UNITED STATES PATENT OFFICE

163,527

GARDEN SPRINKLER

Leon Lewandowski, Omaha, Nebr.

Application April 22, 1950, Serial No. 9,414

Term of patent 7 years

(Cl. D91—1)

To all whom it may concern:

Be it known that I, Leon Lewandowski, a citizen of the United States, residing at Omaha, in the county of Douglas and State of Nebraska, have invented a new, original, and ornamental Design for a Garden Sprinkler, of which the following is a specification, reference being had to the accompanying drawing, forming part thereof.

I claim:

The ornamental design for a garden sprinkler, as shown.

LEON LEWANDOWSKI.
